BLOWOFF MEANS FOR LOCOMOTIVE BOILERS

Otto B. Schoenky, South Pasadena, and Charles
Wesley Sturdevant, San Jose, Calif.

Application December 22, 1941, Serial No. 423,866

4 Claims. (Cl. 122—382)

The present invention relates to a blow-off arrangement for the boilers of steam locomotives. The principal objects of the invention are to provide means for blowing off sludge and water from the bottom of the boiler, and for discharging them at low velocity and in such a position that no damage can ensue to the rails and cross ties of the track, or to auxiliary track structures such as signal wires. A further object is to arrange the discharge in such a manner that steam and mist will not blow back and envelope and condense upon the windows and exterior surfaces of the cars of the train. Still further objects are to provide means for blowing off from either or both sides of the leg of the boiler, to provide an arrangement of pipes that will drain itself completely to prevent freezing, and to provide a device that can be quickly and easily installed on existing locomotives.

Other objects and advantages of the invention will be apparent from the following description, which should be read with the understanding that changes, within the scope of the claims hereto appended, may be made in the form, construction and arrangement of the several parts, without departing from the spirit of the invention.

Reference will be made to the accompanying drawings, wherein

Fig. 1 is a side elevation of the rear portion of a locomotive, showing a preferred embodiment of our invention.

Fig. 2 is a transverse section taken on the line 2—2 of Fig. 1.

Fig. 3 is a side elevation, enlarged, of one of the discharge nozzles.

Fig. 4 is a section on the line 4—4 of Fig. 3.

Fig. 5 is bottom view of the same.

In the drawings, the reference numeral 11 designates the leg of the boiler, at each side of which, near the bottom, is a blow-off valve fitting 12, the valve of which is operated by a lever 13 and a rod 14 from a hand lever 15 in the cab of the locomotive. It is contemplated that there will be two such levers 15, one at each side of the cab, for respectively operating the two valves 12.

From each blow-off valve 12 a pipe or conduit 16 leads downwardly and forwardly, and is provided with an emergency shut-off valve 17 and a union 18. Forwardly of the union 18, the pipes 16 curve inwardly around and in front of the throat sheet, and extend transversely to a point beneath the center of the boiler, where they curve downwardly into a junction fitting or conduit 19. The latter has a vertical branch 20 whose upper

end, shown as closed by a screw plug 21, may be used as a connection for a drain or drains (not shown) from any boiler auxiliaries such as gauge glasses etc.

5 The lower end of the fitting 19 joins a transverse pipe, conduit or manifold 22, extending across the locomotive beneath the boiler and secured to the bed frame 23 by straps 24. The ends of the manifold conduit 22 curve downwardly, as shown at 25, and are further supported by U-bolts 26 from brackets 27 secured to and extending laterally from the bed frame 23. Below the brackets 27, each end of the manifold or conduit 22 divides into two conduit branches 28 directed downwardly at about 45 degrees from the vertical, and each pair of branches terminate in a discharge nozzle, muffler or spreader 29 positioned a few inches outwardly from the side of the trailer truck 30 and far enough above the top of the rail to clear any auxiliary track structures.

Each of the discharge nozzles 29 is formed as shown in Figs. 3, 4 and 5, with an inner cylindrical tubular member 31 preferably welded to manifold branches or conduits 28. Apertures 32 in the upper portion of said tube register with said branches, and horizontal baffles 33 are placed within the tube beneath said apertures. The lower portion of the tube has two parallel rows of holes 34 and 35, the holes 34 being directed outwardly at an angle of about 30 degrees from the vertical, and the holes 35 being directed inwardly at an angle of about 60 degrees from the vertical.

The tubular member 31 is surrounded by an outer shell comprising an outer plate 36 welded to the top of the tube and extending vertically down from the side thereof, and an inner plate 37 welded to the top of the tube and extending on a curve outwardly and downwardly to a point 38 about level with the bottom of the tube, then being bent toward the outer plate at an angle of about 40 degrees from the horizontal, as shown at 39. The bottom edges of the plates 36 and 37 are spaced apart to form a horizontal rectangular discharge opening 40, about 2 inches wide and 24 inches long, the full length of the spreader. The ends of both the tube 31 and the shell are closed by plates 41 welded in place.

The pipes and fittings constituting the described conduits are so proportioned that there is a progressive increase in area from the blow-off valves 12 to the discharge apertures 40. For example, for use with the 24 inch spreaders herein described, the pipes 16 will be one inch in diameter, the junction fitting 19 will be 2½ inches, and the

manifold 22 and branches 28 will be $2\frac{1}{2}$ inches. The combined area of the holes 34 and 35 in each spreader will be greater than the combined area of the two branches 28, and the area of the discharge aperture 40 will be greater than the combined area of the holes 34 and 35. Therefore, there is a progressive decrease in pressure and velocity as the sludge, water and steam pass through the pipes, until they emerge from the discharge apertures 40 at practically atmospheric pressure and with very low velocity. Hence the discharge produces little noise, and is not destructive to the ballast and any auxiliary track structures that it may strike, and does not form a cloud of mist to blow back and be deposited on the windows and exterior surfaces of the cars.

The baffles 33, the holes 34 and 35, and the inclined shell portion 39 so baffle and direct the issuing stream as to cause it to fall harmlessly upon the right of way in a band about a foot or a foot and a half wide, parallel to the rail and several inches beyond the ends of the ties, so that rails, ties, signal wires, and like track structures and appurtenances are not affected by the sludge and water.

The described conduit pipes and fittings are so placed that there are no pockets in which water may be trapped and freeze in cold weather. The pipes 16 are sloped downwardly from the blow-off valves 12 to the central junction fitting 19, and the manifold 22 slopes downwardly from said fitting 19 in both directions to the spreaders 29.

Either blow-off valve 12 may be operated alone, or both may be operated simultaneously. In either case, the discharge is evenly divided at the junction fitting 19, and escapes from the spreaders at both sides simultaneously.

We claim:

1. In a blow-off mechanism for locomotive boilers wherein a valve controlled conduit communicates with and is disposed adjacent the bottom of the boiler and a discharge nozzle communicably connected with said conduit is disposed in a horizontal plane below said valve, the improvement consisting of said discharge nozzle comprising a horizontally disposed elongated tubular member substantially closed at its opposite ends and communicably connected at its upper surface with said conduit for receiving blow-off material therefrom, said member further having a plurality of longitudinally spaced apertures at its lower surface, and a shell surrounding said member and having an outlet positioned for discharging said material downwardly at a point disposed laterally outwardly of the locomotive wheels.

2. In a blow-off mechanism for locomotive boilers wherein a valve controlled conduit communicates with and is disposed adjacent the bottom of the boiler communicating with a manifold extending transversely beneath the boiler, and a discharge nozzle is communicably connected with one end of said manifold; the improvement consisting of providing discharge nozzles at opposite ends of the manifold disposed laterally outwardly of the locomotive wheels, each of said discharge nozzles comprising a horizontally disposed elongated tubular member communicably connected at its upper surface with an end of said manifold for receiving blow-off material including sludge therefrom, each of said nozzles further having a plurality of longitudinally spaced apertures at its

lower surface for discharging said material downwardly therefrom, and a shell open at its bottom enclosing said tubular member, the walls of said shell constituting a baffle for material discharged thereagainst from said tubular member and in turn discharging such material through the open bottom end of said shell at greatly reduced pressure.

3. In a blow-off mechanism for locomotive boilers wherein a valve controlled conduit communicates with and is disposed adjacent the bottom of the boiler communicating with a manifold extending transversely beneath the boiler, and a discharge nozzle is communicably connected with one end of said manifold; the improvement consisting of providing discharge nozzles at opposite ends of the manifold and disposed laterally outwardly of the locomotive wheels, each of said discharge nozzles comprising a horizontally disposed elongated tubular member communicably connected at its upper surface with an end of said manifold for receiving blow-off material including sludge therefrom, each of said nozzles further having a plurality of longitudinally spaced apertures at its lower surface for discharging said material downwardly therefrom, and a shell enclosing said tubular member, said shell having one vertical side and an opposite side sloping inwardly toward said vertical side, the opposite sides of said shell being spaced part and constituting baffles for respectively receiving the impact of and conducting and discharging the blow-off material through an elongated aperture therebetween at a materially reduced pressure.

4. In a blow-off mechanism for locomotive boilers wherein a valve controlled conduit communicates with and is disposed adjacent the bottom of the boiler communicating with a manifold extending transversely beneath the boiler, and a discharge nozzle is communicably connected with one end of said manifold; the improvement consisting of providing discharge nozzles at opposite ends of the manifold and disposed laterally outwardly of the locomotive wheels, each of said discharge nozzles comprising a horizontally disposed elongated tubular muffler member communicably connected at longitudinally spaced portions of its upper surface with an end of said manifold for receiving blow-off material including sludge therefrom, each of said nozzles further having a plurality of longitudinally spaced apertures at its lower surface for discharging said material downwardly therefrom, longitudinally spaced horizontal baffle plates disposed in said muffler adjacent the spaced localities of communication with said manifold for receiving and breaking up the force of impact of the blow-off material admitted to the muffler from said manifold, and a shell enclosing said tubular muffler, said shell having a vertical side and an opposite side sloping inwardly toward said vertical side, the opposite sides of said shell being spaced apart and constituting baffles for respectively receiving the impact of and conducting and discharging the blow-off material received from said muffler member through an elongated aperture disposed between the lower portions of the described vertical and sloping sides of said shell at a materially reduced pressure.
